UNITED STATES PATENT OFFICE

JOHN B. SALTERINI, OF NEW YORK, N. Y.

DESIGN FOR A FLOOR LAMP

Application filed August 21, 1929. Serial No. 32,495. Term of patent 3½ years.

To all whom it may concern:

Be it known that I, JOHN B. SALTERINI, a citizen of the United States, residing at New York, county of New York, and State of New York, have invented a new, original, and ornamental Design for Floor Lamps, of which the following is a specification, reference being had to the accompanying drawing, forming part thereof,

The figure is a perspective view, showing my new design.

I claim:

The ornamental design for a floor lamp, as shown.

JOHN B. SALTERINI.
